DESIGN FOR A TOY WIND-OPERATED DEVICE

Fridolf E. Thoren, Chicago, Ill.

Application August 3, 1939, Serial No. 86,442

Term of patent 7 years

To all whom it may concern:

Be it known that I, Fridolf E. Thoren, a citizen of the United States, residing in Chicago, in the county of Cook and State of Illinois, have invented a new, original, and ornamental Design for a Toy Wind-Operated Device, of which the following is a specification, reference being made to the accompanying drawing, forming a part thereof.

On the drawing,
The single figure is a perspective view of a toy wind-operated device showing my new design.

I claim:

The ornamental design for a toy wind-operated device, as shown.

FRIDOLF E. THOREN.
